GAETANO ARTURO CROCCO AND OTTAVIO RICALDONI, OF ROME, ITALY.

ELASTICALLY-CONNECTED SURFACES FOR INSURING THE STABILITY OF AIRSHIPS,
AEROPLANES, AND SUBMARINE BOATS.

1,038,507.

Specification of Letters Patent. Patented Sept. 10, 1912.

Application filed March 27, 1909. Serial No. 486,123.

To all whom it may concern:

Be it known that we, GAETANO ARTURO CROCCO and OTTAVIO RICALDONI, both subjects of the King of Italy, and captains in the aeronautical brigade in Rome, Italy, have jointly invented certain new and useful Improvements in Elastically-Connected Surfaces for Insuring the Stability of Airships, Aeroplanes, and Submarine Boats, of which the following is a full, clear, and exact specification.

As it is known, in order to insure the stability of dirigible airships and other aerial machines during flight, it is necessary to provide them with steadyng surfaces arranged like fins or otherwise, the object of which is to keep the true direction of the airship in the horizontal as well as in the vertical plane. These steadyng surfaces, which insure steadiness of travel without it being necessary to act continuously on the horizontal or vertical rudders, reach large dimensions, especially when they are applied directly on the gas bag of an aerostat and work in a disturbed air zone, with low efficiency. Therefore, through their adoption the weight and the resistance offered to the movement of aerostats is greatly increased. Other flying machines, such as aeroplanes for instance, also require steadyng tails, which in proportion to the dimension of the apparatus must have a very large surface. Finally self propelling torpedoes, submarine boats, and the like when traveling under water, being in conditions quite similar to those of a dirigible airship in the air, require also self acting rudders in order to insure steadiness of travel.

The object of the present invention is to diminish the surface necessary for securing the stability of the above mentioned moving bodies by making use of planes with increased stabilizing action, provided either at the tail, or both at the head and the tail simultaneously, so that they coöperate both during forward as well as backward movement.

First of all it should be remarked that the stability is to be secured under small angles of deviation from the true direction as it is inadmissible to allow an airship or a submarine in traveling to offer its side to the current of fluid which would impinge thereon with considerable incidence. A limit of 20 or 25 degrees on the right and on the left

can be assumed in practice as the limit of admissible deviations within which the stability is to be insured. In consideration of this, according to the present invention the steadyng surfaces, instead of being formed by fixed planes, are made with movable planes, which can be swung around axes at right angles to the direction of the movement and passing behind the center of pressure on the plane, when they are struck obliquely by the air. It is known that the center of pressure of fluids on inclined planes, is comprised between $\frac{1}{4}$ and $\frac{1}{3}$ of the width, of the plane reckoned from the leading edge and as the incidence increases, this center approaches the geometrical center of the plane, which is reached when the plane is positioned at right angles to the direction of movement. Thus it appears that it will suffice to have the plane pivoted on an axis passing through its geometrical center and perpendicular to the direction of movement in order to be sure that this axis of rotation always remains behind the center of pressure whatever the angle of incidence may be. If the plane were completely free to rotate, in these conditions it would not be steady in its position parallel to the direction of movement but at the slightest deviation it would be upset and tend to lie transversely. However, in order to insure stability in the position of normal travel, and in any other assigned position it will suffice to provide an elastic connection which will resist the upsetting action of the air, and it will then be understood that by suitably regulating this connection it is possible that under the combined action of the air current and of the said connection, the plane, when struck obliquely, will deviate and form an angle of obliquity to its normal position which may be regulated at will, so that the angle at which the current of fluid impinges upon it can be much larger than the angle at which it would be met if rigidly or invariably connected to the moving body, of which it forms a part.

When tail planes are to work together with head rudders, the tail planes are pivoted on an axis situated in the first quarter of the width, reckoned from the rear edge in the direction of the normal movement, and preferably nearer to the rear than to the front end of the said quarter of width. The head rudders, on the contrary, are piv-

oted on an axis situated in the first quarter of their length taken in the direction of the normal movement, and preferably in proximity of the front edge. With this arrangement during forward as well as during the rearward movement, when the moving body deviates from the true direction of its course, the rear plane is deviated from its position of rest more than the body itself producing a strong redressing couple, while the head rudder is deviated to a lesser extent, so that the upsetting couple that it produces is very weak.

The accompanying drawings show diagrammatically some embodiments of the invention, in which—

Figures 1 and 2 show a plan view of the invention as applied to the steadyng plane of an airship in the normal and in a deviated position; Fig. 3 shows a rudder provided with the intensifying device according to the present invention; Fig. 4 shows another embodiment of the tail plane with intensified action; Fig. 5 is a diagram demonstrating graphically the way in which the action of an elastically connected surface varies according to the present invention; Figs. 6 and 7 are a plan and a side elevation respectively of a steadyng plane with an elastic connection for steering a submarine boat in vertical direction; Fig. 8 shows a device arranged inside a submarine boat for acting upon a rudder with elastic connection; Fig. 9 shows diagrammatically the application of the invention to an aeroplane; Fig. 10 shows a device for acting upon a group of multiple planes with elastic connection; Fig. 11 shows a dirigible airship, or submarine boat, with head and rear steadyng planes in position of rest and during the normal travel. Figs. 12 and 13 show the position taken up by the steadyng planes of Fig. 11 and the forces acting upon same respectively in their deviated position during the forward or the backward movement.

Beginning with the case of a caudal steadyng plane for a dirigible airship, Fig. 1, at the tail—1—of the airship, which with its axis x y moves in the direction of the arrow z , there is provided a plane—2—pivoted at—3—on a frame—4—which frame connects same with the after portion of the gas bag. At the point—5—of the plane are secured the ends of two springs—6—7—connected with the frame—4—at the points—8—9. In this position the plane of the rudder coincides with the diametral plane x y of the airship and the springs—6—7—are evenly stretched. From Fig. 2, which shows the same airship, traveling obliquely, viz. when the axis x y forms a certain angle with the direction of movement z , it will be seen how under the action of the pressure of the air indicated by the arrow 65— a —, the plane rotates around its axis—3—

and the angle of the plane with the direction of movement z becomes greater than the angle between said direction of movement and the axis x y . In this case the spring—6—will contract, while the spring—7—⁷⁶ is stretched and the plane will lie in a position, such that the action of the air is balanced by the action of the springs. This position, viz. the angle of final obliquity of the plane, depends only upon the degree of elasticity of the springs, and therefore, other conditions being equal, it can be considerably larger than the angle which forms the axis x y with the direction of movement z .

Fig. 3 shows the same arrangement as in Figs. 1 and 2, in which the points of connection of the springs—6—7—⁸⁴ are connected with ropes—11—12—passing upon guide pulleys—8—⁸⁵ and—9—⁸⁵ and terminating at a controlling lever or wheel, by means of which they may be shifted in such a manner as to permit of operating the above mentioned plane as an ordinary rudder if desired.

In Fig. 4 another embodiment of the invention is shown, in which the position of the plane, instead of being controlled by means of springs disposed at right angles to its faces, is controlled by means of springs—13—disposed longitudinally between the point—5—and a fixed point—14—⁹⁵ of the airship; in this case the action of the springs increases much more rapidly than the angular deviation of the plane. Now it will be understood that, as the pressure on a plane moving obliquely in the air is proportional to the angle of obliquity, the same surfaces of the plane and the same speed of the airship, will produce a considerably greater action in the aforesaid movable plane with elastic connection than would be produced on a fixed plane of the same size and similarly located. As the steadyng action of the plane upon the airship is chiefly due to this pressure, it follows that this action is very much increased by the use of the above described construction.

It will be seen from the above that, while a given fixed plane may not be sufficient to secure any appreciable stability, the same plane, when made movable and elastically connected, will insure sufficient stability to the airship.

Briefly stated the movable planes for insuring stability during the travel act as real automatic rudders. The movable planes can of course be supported in their action by fixed planes, forming a plane partly fixed and partly movable, and the diagram of Fig. 5, calculated for a system of this kind, gives a clear idea of the action of the elastic planes in comparison with that of the fixed planes.

The curve— c — d —represents the negative values of the resultant moment of the

forces counteracting for an airship of about 3000 cubic meters provided with a fixed steadyng plane having a fixed surface of 36 square meters; the curve —a—b— represents the positive values of the resultant moment of the same forces within a field of about 30° on the right and on the left of the same airship under the action of a steadyng plane comprising 12 square meters of fixed surface and 24 square meters of movable surface. Between 0° and 5° the stabilizing action of the movable planes is equal in value to that of about 80 square meters of fixed planes; this multiplying power diminishes as the angle of obliquity increases until for a certain obliquity the action of the movable plane becomes equivalent to the action of a fixed plane.

Supposing a submarine boat having very fine forms of revolution and a displacement of 100 tons and a length of 20 meters and moving under water with a speed of 10 knots, if its shape were similar to the shape of the aforesaid dirigible airship, a horizontal or vertical steadyng keel of 4 square meters would be necessary for balancing the upsetting action of the water. With the use of the elastically connected movable planes according to the present invention a keel of 1 square meter is quite sufficient, provided that springs of suitable power are at disposal. In the case of a submarine boat the springs have to be placed inside the boat, in order to lessen the resistance to the motion; and in this case it will be convenient to pivot the planes at a point placed between $\frac{1}{2}$ and $\frac{1}{4}$ of their width reckoned from the fore edge in the direction of movement in order to diminish the torsional moment on the axis of rotation and the weight of the springs.

Figs. 6 and 7 represent diagrammatically a plan and a vertical section of the arrangement adopted. In the same —1— designates the rear body of the boat, —2— the planes mounted on the shafts —3— which may if desired, be replaced for convenience sake, by a single shaft carrying both planes.

Through the application of the elastically connected movable planes in submarine boats a great advantage in the speed during the subaqueous navigation will be obtained. It is known that the variations of depth for submarine boats by means of the rudders are generally obtained in three ways which are as follows: (a) By the use of simple rudders, generally located at the outer end of the bow; (b) by the use of double rudders rotating in contrary direction at the two ends of the boat; (c) by the use of rudders rotating in the same direction at the two ends of the boat. Of the above systems the first requires the smallest rudder surface area and therefore allows of obtaining the greatest speed; it is, however the most dangerous and the least reliable sys-

tem, because, as large surfaces at the rear, which are necessary to insure stability during the travel, are not available the boat is not steady in its different positions, and its steering requires the continuous attention of the helmsman. Preference is therefore generally given to the third system, known as the parallel sinking system, with which however the surface necessary is so large that the speed of the submarine is considerably diminished.

The arrangement of elastically connected steadyng planes permits of the first system being employed with the greatest safety and without any attention of the helmsman, imparting to the boat absolute stability for any position comprised within the limits of steering. In this case, besides the fixed planes, a stern rudder or a fore rudder can be adopted, or even the fixed planes themselves can be utilized as rudders, by suitably moving the connecting point or points of the springs.

Fig. 8 shows diagrammatically in elevation an embodiment of this system. The rear planes —2— are connected with the shaft —3— carrying a lever arm —4—, the end of which is provided with a spring —6— fixed at one end to the arm —4— and having its other end fastened to a ring secured in a toothed sector —15— concentric with the axis —3— and guided in its movement by connections secured to the body of the boat, which connections are not shown in the drawing. By means of the gears —16— and the worm —17— movement can be transmitted from the handle wheel —18— to the toothed sector —15— so as to displace the fastening point of the spring, whereby the initial inclination of the elastic plane is modified. This arrangement can be employed in self-propelling torpedoes, in which case however the gear 16 will be automatically controlled in the usual manner. The elastically connected rear planes can be advantageously utilized in connection with aeroplanes inasmuch as they reduce to a great extent the surface necessary for insuring stability of the machine in flight.

In order to obviate the disturbances which on account of the energetic action of the elastically mounted planes are produced in the supporting action, they may be connected with front rudders acting in the contrary direction as it will be seen from the Fig. 9. In this figure —19— and —20— represent the tail and the head of the body of an aeroplane; on the tail is pivoted the elastically mounted plane —2— the position of which is controlled by the spring —13— and which carries a rod —21— at right angles thereto. On the head is pivoted a rudder —22— which is also provided with a rod —23— arranged at right

angles thereto. The ends of the two rods are connected crosswise by wires —24— so that the rotations of the two planes take place in opposite directions; any other wire, lever or gearing with which the same effect is obtained can be employed. While the elastically mounted plane produces a certain depressing power, the front rudder produces contemporaneously a certain elevating force or vice versa. The moments of the two forces can be equal in value, or the moment of the upwardly directed force may be greater, if this is more convenient. In this way the resultant moment of the stabilizing forces is increased without impairing the supporting action of the whole of the aeroplane. In the figure both the supporting planes and the propeller are omitted for the sake of clearness. Finally in all machines, to which the elastically mounted planes can be applied, it is possible to employ sets of superposed planes.

Fig. 10 shows the stabilizing system of a dirigible airship. There are three sets of planes —2'—2''—2'''— which are pivoted at —3'—3''—3'''— and connected together by means of a rigid rod —25— jointed at —5'—5''—5'''—. The springs —6—7— are connected at —5''— only with the central plane. The spring —6— is fastened to the fixed point —26— of the airship. The point —27—, which is also fixed on the airship, carries a pulley, around which passes rope —28—, to one end of which is fastened the spring —7— and on the other a handle-wheel for the control of the elastic planes (not shown). In this way the planes can be controlled by means of one rope only.

The application of stabilizing planes at both ends of a vessel is shown by Figs. 11, 12, 13 which represent diagrammatically the arrangement of the members in the case of a dirigible airship, or of a submarine boat, which moves in the direction shown by the arrow z . In the said figures the outline of the body of the dirigible airship, or of the hull of the boat to which the planes are applied, is shown in dotted lines. The rear planes —2— are pivoted on an axis —3— and balanced by the front spring —13— secured at —14—. The front rudders —22— are pivoted upon an axis —29— and balanced by the rear spring —30— secured at —31—. The axis of rotation —3— is located in the last quarter of the width of the plane reckoned from the front edge in the direction of the normal movement and very near the rear edge. The axis of rotation —29— is located in the first quarter of the width of the rudder reckoned from the front edge in the direction of the normal movement and very near the front edge. It will be understood that the springs can be arranged in any other way according to the particular circum-

stances involved in the construction to which they are applied. When the movable body during its forward travel deviates for instance toward its left hand side, as shown Fig. 12, the forces —a— and —b— act against the planes —2— and —22—.

The rear planes, working in the aforesaid manner will increase the angle of obliquity, while the front planes, in which the center of pressure falls behind the axis of rotation, will reduce the angle of obliquity. It follows that the upsetting moment of the force —b— acting on the front planes is very weak, while the moment of the force —a—, on the rear planes counteracting the deviation is very strong. In this way it is possible to utilize the front planes as rudders by acting on the fastening point —31— of the spring —30— or in any other way, without disturbing the equilibrium. Further the system permits of rearward movement while preserving the stability, which would not be possible with the steering devices now in use for dirigible airships and submarine boats. In fact, as will be clearly seen from Fig. 13, during rearward movement, and for an oblique position of the axis with respect to the direction of the movement, the action is reversed. The rear planes —2— will diminish their angle and produce the force, —a—, having a very weak disturbing moment while the front planes —22— increase their angle and produce force —b— having a very strong redressing moment. As during the forward motion the force —a— is applied farther away from the axis of rotation —3— and the force —b— nearer the axis of rotation —29— than during the rearward movement, it is clear that the springs —13—30— the tension of which is regulated for the forward motion do not comply well with the requirements in the case of the rearward motion, during which it will be necessary to weaken the action of the springs —13— and to strengthen that to the spring —30—. This result can be obtained with a single movement which displaces in the same direction, viz. toward the stern, the fastening points —14—31— of the two springs, and which can be produced by a fore-and-aft-direction lever being within the helmsman's reach who will shift it in the position required.

Claims.

1. A self acting steadyng device for bodies moving in a fluid, as dirigible airships, aeroplanes, self propelling torpedoes, submarine and submergeble boats and the like, comprising: movable planes provided at the tail of the moving body; shafts carrying said planes and around the axes of which the planes can be swung, placed at right angles to the direction of the movement and behind the center of pressure of the fluid acting on the plane, when the latter is moving

obliquely, and elastic connections between the movable planes and the moving body conveniently disposed to counteract the action of the fluid impinging obliquely on the plane 5 and to stop the latter in a position in which its angle of deviation is greater than the angle of deviation of the axis of the moving body, for the purposes set forth in the specification.

10 2. A self acting steadyng device for bodies moving in a fluid, as dirigible airships, aeroplanes, self-propelling torpedoes, submarine and submergible boats and the like, comprising: movable planes provided 15 at the tail of the moving body; shafts carrying said planes and around the axes of which the planes can be swung, placed at right angles to the direction of the movement and behind the center of pressure of the 20 fluid acting on the plane when the latter is moving obliquely; elastic connections between the movable planes and the moving body conveniently disposed to counteract the action of the fluid impinging obliquely 25 on the plane and to stop the latter in a position in which its angle of deviation is greater than the angle of deviation of the axis of the moving body; and means whereby the points to which the elastic connections are secured to the moving body can 30 be shifted in order to cause the movable planes to act as ordinary rudders, for the purposes set forth in the specification.

3. A self acting steadyng device for bodies moving in a fluid as dirigible airships, self-propelling torpedoes, submarine and submergible boats and the like, comprising: movable planes provided outside the hull 35 of the moving body; shafts carrying said planes and around the axes of which the planes can be swung, placed at right angles to the direction of the movement and behind the center of pressure of the fluid acting on the plane, when the latter is moving 40 obliquely; extensions of said shafts projecting inside the hull of the moving body, and elastic connections placed also inside the hull 45

and operating on members fastened to said extensions of the supporting shafts, and conveniently disposed to counteract the action 50 of the fluid impinging obliquely on the plane and to stop the latter in a position in which its angle of deviation is greater than the angle of deviation of the axis of the moving body, for the purposes set forth in the 55 specification.

4. A self acting steadyng device for bodies moving in a fluid as dirigible airships, self-propelling torpedoes, submarine and submergible boats and the like, comprising: movable planes provided outside the hull of the moving body; shafts carrying said planes and around the axes of which the planes can be swung, placed at right angles to the direction of the movement and behind the center of pressure of the fluid acting on the plane, when the latter is moving obliquely; extensions of said shafts projecting inside the hull of the moving body; elastic connections placed also inside the 60 hull between members fastened to said extensions and points of the hull and conveniently disposed to counteract the action of the fluid impinging obliquely on the plane and to stop the latter in a position in which 65 its angle of deviation is greater than the angle of deviation of the axis of the moving body; and means whereby the points to which the elastic connections are secured to the moving body can be shifted so that the 70 steadyng planes may also act as a horizontal rudder for varying the longitudinal inclination of the boat and thus also the depth of navigation, for the purposes set forth in 75 the specification.

In witness whereof we have hereunto set our hands in the presence of two subscribing witnesses.
